PAPER HOLDER OR THE LIKE

John A. Helgesen, 900 Boulevard Drive, Belpre, Ohio

Filed May 17, 1962, Ser. No. 70,182

Term of patent 14 years

(Cl. D74—5)

Fig. 2

FIG. 1 is a perspective view of a paper holder or the like, showing my new design; and

FIG. 2 is a cross-sectional view of the holder taken on lines 2—2 of FIG. 1.

The side not shown is the same as the side shown.

I claim:

The ornamental design for a paper holder or the like, as shown and described.
